UNITED STATES PATENT OFFICE.

CLARENCE L. GROVES, OF HARTFORD CITY, INDIANA, ASSIGNOR, BY DIRECT AND MESNE ASSIGNMENTS, OF ONE-HALF TO GEORGE R. MYERS AND ONE-HALF TO R. J. D. LARMOYEUX, OF HARTFORD CITY, INDIANA.

PNEUMATIC CONVEYER.

No. 843,806.

Specification of Letters Patent.

Patented Feb. 12, 1907.

Application filed April 27, 1906. Serial No. 314,028.

To all whom it may concern:

Be it known that I, CLARENCE L. GROVES, a citizen of the United States, residing at Hartford City, in the county of Blackford 5 and State of Indiana, have invented new and useful Improvements in Pneumatic Conveyers, of which the following is a specification.

This invention relates to pneumatic conveyers or elevators such as are used for transporting grain and similar material, although they may be used for other purposes, if desired.

Pneumatic conveyers of the class indicated 15 as heretofore constructed have been provided with a fan-chamber having a lateral inlet and a tangential outlet for the grain. This form of conveyer is objectionable by reason of the fact that it is necessary for the 20 grain to turn at an angle after entering the fan-chamber from the side in order to pass out through the tangential outlet.

The object of my invention is to improve the construction of pneumatic conveyers by 25 dispensing with the side inlet and employing a tangentially-arranged inlet whereby to increase the strength and to decrease the amount of power necessary for operating the fan.

With the forgoing and other objects in 30 view, which will appear as the description proceeds, the invention resides in the combination and arrangement of parts and in the details of construction hereinafter described 35 and claimed.

In the accompanying drawings, forming part of this specification, Figure 1 is a side elevation of a pneumatic conveyer constructed in accordance with the invention. Fig. 2 40 is a plan view thereof. Fig. 3 is a vertical section, partly in elevation. Fig. 4 is a transverse section on the line 4-4 of Fig. 3.

Like reference - numerals indicate corresponding parts in the different views of the 45 drawings.

The reference - numeral 1 indicates the frame or support of the conveyer, which may be of any suitable form and construction.

The numeral 2 indicates the fan-chamber, 50 which preferably is circular in form. Secured to each side of the fan-chamber 2 is an integral casting 3, having attaching-lugs 4, which are fastened to the fan-chamber by bolts or

other suitable devices 5. Each of the castings 3 is formed with a journal-box 6, through 5 which extends the fan-shaft 7. The castings 3 rest upon the framework 1, and thus serve to support the fan-chamber and fan-shaft in a thoroughly efficient and inexpensive manner.

Suitably secured upon the fan-shaft 7 are the fan-blades 8, which may be of any desired form and construction.

Leading into the fan-chamber 2 is an upwardly-inclined feed-pipe 9, which is tangentially arranged with respect to the fan-chamber, as shown clearly in Fig. 3. At the point where the feed-pipe 9 joins the fan-chamber 2 an air-inlet 10 is formed in the fan-chamber to permit the entrance of air 70 during the rotation of the fan.

Removably fitted into the upper end of the feed-pipe 9 is a bell-pipe or flared hopper 11. While the bell-pipe 11 may be held in place in any suitable manner, said pipe is preferably 75 secured in position by means of a flange or lip 12, which is secured thereto in such a manner as to fit over the upper edge of the feed-pipe 9, as shown in Figs. 2 and 3. The lower flattened end of the bell-pipe or hopper 11 80 preferably is of less width than the upper flattened end of the feed-pipe 9, for which reason air-inlets 13 are provided on opposite sides of said pipe 11, as shown clearly in Fig. 2.

In order to clean the interior of the fan-chamber whenever necessary or desirable, a sliding door 14 is provided in the lower portion thereof. Adjacent to the sliding door 14 the fan-chamber is provided with a tangentially-arranged outlet-pipe 15, to which is 90 suitably secured a conveying-pipe 16. The conveying-pipe 16 is provided with a pair of branch pipes 17 and 18 in the usual manner. The conveying-pipe 16 is also provided with a suitable deflecting gate or valve 19, having 95 a handle 20, by means of which the grain may be deflected into either one or the other of the branch pipes 17 and 18.

While the fan 8 may be driven in any suitable manner it is preferable that said fan be 100 operated by means of a small belt-wheel 21, and that it be provided with a large balance-wheel 22.

Constructed as hereinbefore described the 105 operation of the improved conveyer will be apparent. Grain or other material is dumped

into the hopper 11 and is drawn down into the fan-chamber by the suction of a fan, this indrawing of the grain being facilitated by the suction of air through the openings 13 and through the air-inlet 10. It is found in practice that a pneumatic conveyer of the character described possesses many advantages over conveyers in which the grain enters the fan-chamber through openings in the sides thereof adjacent to the fan-shafts.

Changes in the precise embodiment of the invention illustrated and described may be made within the scope of the following claims without departing from the spirit of the invention or sacrificing any of the advantages.

What I claim is—

1. A pneumatic conveyer having a fan, a fan-chamber, a tangential feed-pipe, an air-inlet to the fan-chamber adjacent to the point where the tangential feed-pipe connects with the chamber, a door in the lower portion of the fan-chamber, and a tangential outlet-pipe.
2. A pneumatic conveyer having a fan, a fan-chamber, a tangential feed-pipe, an air-inlet to the fan-chamber adjacent to the point where the tangential feed-pipe connects with the chamber, a door in the lower portion of the fan-chamber, and a tangential outlet-pipe having a pair of branch pipes connected thereto and a gate or valve therein for deflecting the grain into either one of the branch pipes.
3. A pneumatic conveyer having a fan, a fan-shaft, a fan-chamber, integral castings secured to the sides of the fan-chamber and

formed with journal-boxes for the fan-shaft, a supporting-frame connected with the castings, a tangential feed-pipe leading into the fan-chamber, and a tangential outlet-pipe for the fan-chamber.

4. A pneumatic conveyer having a fan, a fan-chamber, a tangential feed-pipe, a hopper connected with the upper end of the said feed-pipe and being smaller at its lower end than said feed-pipe so as to provide a plurality of air-inlets at the upper end of the feed-pipe, and a tangential outlet for the fan-chamber.

5. A pneumatic conveyer having a fan, a fan-shaft, a fan-chamber, integral castings secured to the sides of the fan-chamber and formed with journal-boxes for the fan-shaft, an upwardly-inclined tangential feed-pipe leading into the fan-chamber, an air-inlet to the fan-chamber adjacent to the tangential feed-pipe, a hopper having a flange fitting over the upper edge of the feed-pipe and being smaller at its lower end than the feed-pipe so as to provide a plurality of air-inlets, a sliding door in the lower portion of the fan-chamber, a tangential outlet adjacent to the sliding door, a conveying-pipe having a deflecting-valve, and a pair of branch pipes connected with the conveying-pipe and controlled by the deflecting-valve.

In testimony whereof I affix my signature in presence of two witnesses.

CLARENCE L. GROVES.
